UNITED STATES PATENT OFFICE.

FRANK J. DRUAR, OF DETROIT, MICHIGAN, ASSIGNOR TO PACKARD MOTOR CAR COMPANY, OF DETROIT, MICHIGAN, A CORPORATION OF MICHIGAN.

RADIATOR COVER.

Application filed January 3, 1919. Serial No. 269,427.

To all whom it may concern:

Be it known that I, FRANK J. DRUAR, a citizen of the United States, and residing at Detroit, county of Wayne, State of Michigan, have invented certain new and useful Improvements in Radiator Covers, of which the following is a specification.

The present invention relates to motor vehicle radiators and more particularly to means for reducing the cooling effect thereof.

During the winter it is customary to use a so-called "hood" or "cover" over the radiator or hood and radiator together, for the purpose of offsetting the greater cooling effect that would otherwise result from the low temperatures of the atmosphere. Such covers are more or less clumsy and unsightly. Furthermore, being on the outside of the radiator or hood they are exposed to the weather and soon become shabby in appearance.

The present invention aims to remedy the above and other defects of the covers heretofore used, and to these ends consists in the provision of heat insulating material between the core and shell of the radiator.

The objects and novel features of the invention will be apparent from the description taken in connection with the drawings in which:—

Figure 1 is a perspective view of a radiator, insulated in accordance with the present invention, some of the parts being broken away to clearly show the insulation;

Figure 2 is a perspective view of a radiator shell;

Figure 3 is a front elevation of a curtain adapted to be secured to the edges of the insulation and close the usual air aperture in the shell;

Figure 4 is an enlarged sectional elevation, taken substantially on the line 4—4 of Figure 1; and

Figure 5 is an enlarged sectional plan taken substantially on the line 5—5 of Figure 1.

Referring to the drawings it will be seen that they illustrate a radiator of usual construction, that is, one having a core indicated in general by the reference numeral 10 and a removable shell 11 disposed around the core. Usually, the shell is secured to the core by having its rear flange 12 bolted

or otherwise fastened to a series of tongues or fingers 13 projecting rearwardly from the core. As clearly shown in Figure 5 the shell has a portion 14 which projects a slight distance over the front of the core, leaving an aperture 15 for the air to pass through the radiator. If desired, the edge of the flange 14 bounding the aperture 15 may be formed with a bead 16.

According to the present invention, in order to keep the temperature of the fluid within the radiator as nearly constant as possible during cold weather and also in order to offset the excessive cooling action due to the low temperatures obtaining in winter, heat insulating material 17 is disposed around the periphery of the core between the core and the shell. Preferably, this material is in the form of a blanket 17 which is shaped to the contour of the radiator core and at the front of the core is provided with an overhanging portion 18. Preferably, this portion 18 projects slightly within the bead 16 of the shell, thereby providing a flap or lip 19 to which may be secured a curtain 20 for the purpose of regulating the size of the opening 15.

As shown in the drawings the blanket 17 may consist of two outside layers of fabric 21 with an interposed layer 22 of felt or other suitable material. The layers are secured together in any suitable manner as by means of the stitching 23.

From the foregoing description it will be seen that the blanket 17 may be easily put on or removed from the core after the shell 11 has been taken off, so that the blanket 17 may be placed on the core at the beginning of winter and removed at the end of the cold period without the services of a skilled mechanic.

The curtain 20 is preferably secured to the flap 19 by means such as glove fasteners 24, and may be of any suitable construction but preferably is made up in sections, as shown in Figure 3. Thus the curtain may be formed with the two parallel horizontally extending thin or flexible portions 25 and 26 whereby the upper section A may be turned down about the flexible or hinge portion 25 and secured flat against the section B by the glove fasteners 27. In this manner about one-third of the usual aperture 15 is open

and the remainder covered by the blanket. If it is desired to have a larger air passage through the radiator then the two sections A, B, may be turned down as a unit about the hinge portion 26 and secured against the lower section 3 of the curtain by the fasteners 28. Finally, if it is desired to have the entire opening 15 free, the curtain may be entirely removed by unclasping the glove 10 fasteners 24. While a curtain of the construction just described is preferred, the curtain by itself is not included in the present invention but is described and claimed in a co-pending application Serial Number 15 269,428, filed January 3, 1919.

Although an embodiment of the invention has been described in detail it is to be understood that the invention is not thus limited but includes modifications and 20 changes which come within the scope of the appended claims.

Having thus described the invention what

is claimed as new and desired to be secured by Letters Patent is:—

1. A motor vehicle radiator comprising 25 in combination, a core, a removable shell surrounding the core and having an opening for air to pass through the core, a blanket disposed between said core and shell and projecting slightly beyond the edge of 30 the shell bounding said opening, and a curtain closing said opening and detachably secured to the projecting portion of the blanket.

2. The combination with the core and surrounding shell of a motor vehicle radiator, of heat insulating material disposed between said core and shell, a curtain disposed to close the air opening in the front of the radiator, and means to detachably fasten 40 said curtain to said material.

In testimony whereof I affix my signature.

FRANK J. DRUAR
